DESIGN FOR A SAVINGS BANK

Alexander S. Ewald, South Bend, Ind.

Application May 12, 1944, Serial No. 113,570

Term of patent 7 years

(Cl. D34—11)

To all whom it may concern:

Be it known that I, Alexander S. Ewald, a citizen of the United States of America, residing at South Bend, county of Saint Joseph, and State of Indiana, have invented a new, original and ornamental Design for a Savings Bank, of which the following is a specification, reference being had to the accompanying drawing, forming a part thereof wherein:

I claim:

The ornamental design for a savings bank, as shown.

ALEXANDER S. EWALD.
